UNITED STATES PATENT OFFICE.

CLAUDE V. FULLER, OF NEW YORK, N. Y.

ANTISEPTIC TELEPHONE-MOUTHPIECE.

1,032,596.

Specification of Letters Patent. Patented July 16, 1912.

Application filed February 28, 1912. Serial No. 680,459.

To all whom it may concern:

Be it known that I, CLAUDE V. FULLER, a citizen of the United States, residing at New York, in the county of New York and State of New York, have invented certain new and useful Improvements in Antiseptic Telephone-Mouthpieces, of which the following is a specification.

My invention relates to antiseptic guards for telephone mouth pieces or transmitters.

One of the objects of the invention is to provide antiseptic guards which may be readily attached to or detached from the usual type of telephone mouth pieces.

Another object of the invention is to provide a guard of the character described which will automatically fasten itself to the outer edge of the transmitter.

Another object of the invention is to provide a guard which is initially treated to render possible the formation of the fastening means.

A still further object of the invention is to provide an antiseptic guard which may be manufactured at a minimum cost, thereby permitting its general use so that it may be discarded when desired without any appreciable or material loss.

To the accomplishment of the recited objects and others coördinate therewith, the preferred embodiment of my invention resides in that construction and arrangement of parts hereinafter described, illustrated in the accompanying drawings, and embraced within the scope of the appended claims.

In said drawings: Figure 1 is a perspective view of a telephone transmitter illustrating the application of my invention. Fig. 2 is a sectional elevation of the antiseptic guard and the mouth piece of the transmitter. Fig. 3 is a front elevation of the guard detached, and Fig. 4 is a sectional elevation of a portion of the guard showing the antiseptic coating.

Generally speaking, the invention comprises a single piece of paper arranged to present a substantially conoidal form and treated with any suitable antiseptic composition, the main body portion of the paper being fluted or otherwise constructed so that the outer marginal edge thereof may be bent rearwardly and again forwardly upon itself to form a fastening means which coöperates

with the corresponding outer edge or rim of the mouth piece or transmitter.

55

Referring more particularly to the drawings for a detail description of my invention, the numeral 1 designates the antiseptic guard formed of a single piece of material, as paper or the like, and having a conoidal contour with a perforated wall 2 and a body portion 3 projecting therefrom. The body portion is longitudinally fluted at 4, and these flutes extend from the wall 2 in radial lines to the extreme edge of the body 3. The outer marginal edge of the body 3 is bent rearwardly at right angles to the latter, as at 5, to present an annular flange, and in turn, a portion of this flange is flexed forwardly, as at 6. In this connection, it will be pointed out that the fluting of the material renders the formation of the flanges just described with facility. The antiseptic coating is indicated by 7 in Fig. 4.

65

In practical operation the guard 1 is grasped in the hand and gently forced into the transmitter 8 of a telephone, whereupon the inwardly disposed flange 6 will ride over the extreme outer edge of the transmitter until the latter occupies a position contiguous or contacting with the material of which the guard is formed at the junction of the body 3 and the angularly deflected flange 5. When the device has been caused to assume this position the flange 6 will, because of its inherent resiliency, spring inwardly so that the extreme edge thereof will engage the outer proximal end of the transmitter 7, but in a line below the extreme or distal end of the transmitter. By virtue of the foregoing arrangement the flange 6 will act in the capacity of a locking or fastening means, and preclude any possibility of the antiseptic guard becoming accidentally removed or displaced relative the transmitter. At the same time, however, the engagements of the flange 6 is such that the entire guard may be easily removed from the transmitter when the occasion requires. Upon removing the device, it will be manifest that the flange 6 will be forced up the outer incline portion of the marginal edge of the transmitter and will lie sufficiently flat to allow an easy detachment.

105

What is claimed, is:

1. An antiseptic guard for telephone

mouth pieces, comprising a hollow body portion having substantially the form of a truncated cone and its outer marginal edge turned rearwardly and then forwardly to engage the outer portion of the mouth piece.

2. An antiseptic guard for telephone mouth pieces, comprising a hollow body portion having substantially the form of a truncated cone and its outer marginal edge 10 rearwardly and forwardly disposed, the for-

wardly disposed portion being adapted to engage the periphery of the mouth piece and maintain the rearwardly disposed portion removed therefrom.

In testimony whereof I hereunto affix my 15
signature in presence of two witnesses.

CLAUDE V. FULLER.
